Primary Examiner—M. N. Pandozzi*(74) Attorney, Agent, or Firm*—Dann, Dorfman, Herrell and Skillman; Henry H. Skillman**CLAIM**

The ornamental design for a single cool/hot water dispenser, as shown and described.

DESCRIPTION

FIG. 1 is a perspective view of a first embodiment of a single cool/hot water dispenser showing the design;

FIG. 2 is a front view thereof;

FIG. 3 is a rear view thereof;

FIG. 4 is a left side view thereof, the right side view thereof being a mirror image;

FIG. 5 is a top plan view thereof;

FIG. 6 is a bottom plan view thereof; and,

FIG. 7 is a left side view thereof.

The broken line showing of a tube and bottle in FIG. 7 is for illustrative purposes only and forms no part of the claimed design.
